Harold P. Post, 150 Huyshope Ave., West Hartford, Conn.

Filed Sept. 1, 1965, Ser. No. 86,794

Term of patent 14 years

(Cl. D80—9)

FIG. 3

The dominant features of my design reside in the portions shown in full lines.

I claim:

The ornamental design for a combined demonstration and display stand, as shown and described.
